H. KIELBERG

FRONT SUPPORT FOR GAS HEATERS

Filed April 16, 1924

UNITED STATES PATENT OFFICE.

HENRY KIELBERG, OF MARTINS FERRY, OHIO, ASSIGNOR TO WHEELING STEEL CORPORATION, OF WHEELING, WEST VIRGINIA, A CORPORATION OF DELAWARE.

FRONT SUPPORT FOR GAS HEATERS.

Application filed April 16, 1924. Serial No. 706,974.

To all whom it may concern:

Be it known that I, HENRY KIELBERG, a citizen of the United States of America, and resident of Martins Ferry, county of Belmont, and State of Ohio, have invented certain new and useful Improvements in Front Supports for Gas Heaters, of which the following is a specification.

This invention relates broadly to gas heaters, and more specifically to front supports for such heaters.

The primary object of the invention is to provide, in a gas heater, front supporting posts of pedestal type having simple and comparatively inexpensive members or wings whereby they are connected to the heater body.

A further object is to provide, in association with the body of a gas heater, a novel and pleasingly ornamental form of wing whereby said body is connected to a supporting post or pedestal located laterally and forwardly with respect to said body.

In describing the invention in detail, reference is herein had to the accompanying drawings, in which—

Figure 1 is a front elevation of a gas heater embodying my invention;

Figure 2 is a side elevation of the same;

Figure 3 is a sectional elevation taken substantially on line 3—3, Fig. 1;

Figure 4 is a section on line 4—4, Fig. 3.

Referring to said drawings, 1 indicates generally the body of a gas heater of the open front radiant type, which may have one or more rear supporting legs, as 2.

Located at any appropriate distance forwardly of the general plane of the front of the heater body, and also laterally of the plane of each of the ends of said body, is an upright supporting pedestal or post 3 adapted to serve as a support of andiron type for the front of said heater body; that is to say, the posts 3 are designed to complement the rear legs or leg 2 in supporting the heater body and, in their forwardly and laterally disposed positions, to greatly enhance the appearance of the heater. Each of the posts 3, which are of materially less height than the heater body, comprises a body, herein shown as of cylindrical form, having a pair of rearwardly directed verti-

cal flanges 4. Attached to said flanges, as by means of bolts 5, is the front edge of a wing-like member 6 which has its opposite, 55 or rear, edge attached, as by means of bolts 7, to the adjacent front corner portion of the heater body 1.

The wing 6, which is formed of a single sheet metal blank, is disposed vertically and is preferably of arcuately curved form in horizontal section, presenting its concave face forward, as shown. The top and bottom edges of said wing are bent over into bead or roll form, as shown at 8 and 9, for 60 the dual purpose of stiffening or reinforcing and of ornamenting said wing. Furthermore, while the rearmost edge of each wing has a length approximating that of the heater body 1, the foremost edge is of 65 greatly reduced length, being herein shown as having a length approximating one half that of said rearmost edge.

For the purpose of affording additional strength and rigidity, when such is required, 70 a suitable brace 10 may be interposed between each of the posts 3 and the adjacent end of the heater body, said brace being located rearward of the adjacent wing 6 and being concealed by the latter when the 75 heater is viewed from in front. It will be understood, however, that the brace may not be essential, especially in connection with heaters of small size or light weight.

What is claimed is—

In a radiant gas heater, the combination with a heater body, of supporting pedestals located forwardly and laterally of and at a substantial distance from the front corners of said body, said pedestals having vertical 90 rearwardly-directed flanges, and vertically disposed sheet metal wings interposed between said pedestals and said body, each wing being bolted at one end to said flange and at its other end to the adjacent corner 95 portion of said body, said wing having stiffening rolls formed thereon, and braces connecting said pedestals to the body and located rearwardly of and concealed by said wings, said braces relieving said wings from 100 strain.

In testimony whereof, I affix my signature.

HENRY KIELBERG.
